(57) CLAIM

The ornamental design for a syringe needle for catheter, as shown and described.

DESCRIPTION

FIG. 1 is a front perspective view of a syringe needle for catheter, showing our new design;

FIG. 2 is a rear perspective view of FIG. 1;

FIG. 3 is a front elevation view of FIG. 1 and the rear view is a mirror image thereof;

FIG. 4 is a left side elevation view of FIG. 1;

FIG. 5 is a right side elevation view of FIG. 1;

FIG. 6 is a top plan view of FIG. 1;

FIG. 7 is a bottom plan view of FIG. 1;

FIG. 8 is a front perspective view of the syringe needle for catheter in which the inner needle is put in the body with the spring shrunk and the outer needle removed; and,

FIG. 9 is a perspective view of the syringe needle for catheter of our new design with a cap. The broken lines in the drawings depict an example of a cap and form no part of the claimed design.
